UNITED STATES PATENT OFFICE.

JOHN G. BALSILLIE, OF MELBOURNE, AUSTRALIA.

REFLECTOR FOR USE IN LIGHT PROJECTORS.

Application filed February 15, 1923. Serial No. 619,225.

To all whom it may concern:

Be it known that I, JOHN G. BALSILLIE, a subject of the King of Great Britain, residing at Melbourne, Australia, have invented 5 certain new and useful Improvements in Reflectors for Use in Light Projectors, of which the following is a specification.

This invention relates to reflectors and has for its object the production of a beam 10 of light which in cross section has the shape of an elongated ellipse considerably wider in the middle than at its ends and with the rays of light concentrated to a beam, said beam having a contour of equal intensities 15 in the shape approximately of an isosceles triangle, and wherein the maximum light intensity is positioned in a zone occupying the middle of the triangle such as is required by many State statutes relating to 20 motor vehicle headlamps.

Another object of the invention is to produce a surface which, while made up of a number of meeting surfaces of different curvatures will be free of sharp grooves 25 which interfere with the buffing production process.

Another object of the invention is to produce a reflector having as nearly a stigmatic surface of revolution as possible to facilitate manufacture and cheapen production. 30

With these and other objects in view which will appear as this specification proceeds, my invention will be described in connection with the accompanying drawing in 35 which:

Figure 1 is a diagrammatic front view of my reflector showing the wedge-shaped zones or surfaces and also that the planes 40 passing through the edges of the zones or surfaces converge to a small area on one side of the reflector;

Fig. 2 is a diagrammatic view of a modified construction wherein the zones or wedge-shaped surfaces comprising the upper and 45 lower parts of the reflector taper in opposite directions from a plane passed through the horizontal diameter of the reflector;

Fig. 3 represents a second modification;

Figs. 4 and 5 represent modifications 50 wherein the wedge-shaped surfaces only comprise a portion of the entire surface of the reflector, a relatively small portion being a stigmatic surface of revolution;

Fig. 6 is a graphic representation of two 55 tapered surfaces illustrating that the bound-

ing edges of each surface are of different oblique sections of the same stigmatic surface of revolution and also graphically showing that the elements of the surface of each section converge on differently positioned loci;

Fig. 7 is a diagrammatic representation of the shape of light areas of uniform light intensities required by many State statutes and relative intensities of illumination approximated by applicant's reflector;

Fig. 8 is a diagrammatic representation of a cross section of the various beams projected by the several surfaces comprising the left half of the reflector shown in Fig. 9;

Fig. 9 is an enlarged view of my reflector;

Fig. 10 is a section of the reflector shown in Fig. 9 on the line 10—10 thereof.

The laws of many States require that the quantity of light projected by two motor 75 vehicle head lights must be substantially that indicated in Fig. 7, the contour lines joining points of equal light intensity at 100 feet distant from the head lights when a light source of 21 candle power is positioned 80 at the focal point of each reflector, the values being in apparent candle power.

My present invention has, therefore, primarily for its object the provision of a reflector which will project a beam of light, 85 the cross section of which will be as hereinbefore specified. Such light distribution as occurs beyond the legally specified area is designed to utilize the excess light to the best advantage, but the light distribution 90 within the specified area will of course be in accordance with requirements.

I accomplish this object by distorting a surface of revolution of a conic section into a number of wedge-shaped surfaces A', A², A³, etc., each surface being bounded by planes which diverge from a small area B positioned on or about a plane C passed through the axis D of the reflector T.

The bounding edges F of each wedge-shaped surface A', A², A³, etc., conform to the surface of revolution of the same conic section. The elements G, Fig. 6 of each wedge-shaped surface A', A², A³, etc., are preferably straight and these elements converge to differently positioned loci H and H', etc. These loci are always located beyond the reflector. As shown in Fig. 6 the surfaces are distorted from surfaces of revolution and are so shaped that 110

if the elements are produced beyond the bounding edge they will converge as shown in that figure.

For optical as well as manufacturing reasons I prefer to leave between the bounding edges, F, F of each section A', A², A³, etc., portions of the original surface of revolution. These are illustrated at S, S, etc., Figs. 1 to 5, 9 and 10. The effect of making the elements G, Fig. 6 of all tapered surfaces A', A², A³, etc., radiates from loci H, H', etc., positioned beyond the reflector, and at the same time maintaining at the bounding edge of each tapered surface the curvatures of the surface of revolution, as represented at F, F, etc., is to displace or skew the projected beam so that its apparent axis is as shown at K', K², etc., Fig. 8 of the sections A', A², A³, etc. The amount of the skewing or displacement of the rays is approximately equal to the angle enclosed by the bounding planes, and the axial plane C, such portions of the reflector surface as are of the curvature of the surface of revolution (shown in Figs. 4 and 5) operate to patch up the light in the axial center of the projected beam. This gives the designer some latitude for errors in manufacture.

Sharp angles or meeting lines of sections are undesirable because of filling up with buffering powder which is difficult to remove, hence the small interspersed sections S, S, etc., have considerable production advantages. These interspersed surfaces may not be always sufficient for the desired patching up in which case designs as shown at U in Figs. 4 and 5 may then be resorted to.

It should be clearly understood that the light pattern shown in Fig. 7 is merely a graphic representation of the light distribution specified by the law.

The reflectors are nearly stigmatic in shape and consequently the general form of the area they illuminate will be the same elliptical shape. However, the distribution of the light within this area will vary somewhat but may be caused to stay within the prescribed limits. By varying the position of the loci H, H' of the designs shown in Figs. 2, 3, 4 or 5 I may make the contour of each surface A', A², A³, etc., project a beam of light so that the light distribution in the illuminated area is substantially the same as that projected by the design shown in Fig. 1.

The tables appended apply to the hyperbola of 6° divergence with 1.22 inch focus. I particularly mention hyperbola as otherwise much difficulty would arise in imparting the requisite curvature to the elements of each section to obtain the desired light spread and distribution from each section.

The projected light pattern of each section

A', A², A³, etc., will be of the shape as shown at a', a², a³, etc., Fig. 8. Points of uniform light intensity of each light pattern are joined by lines as indicated at R in Fig. 8. The beam from each section is axially displaced an amount dependent upon its location on the reflector surface. Thus the beam of light from section A' nearest to the rim of the reflector T, Figure 9, will be displaced as shown at a'. Figure 8 and the beam of light from A², Fig. 9 will be displaced as shown at a² Fig. 8, etc.

It will thus be seen that the cross section of the light intensity pattern, the left half of which is shown in Fig. 8 when projected by the reflector as a whole will be of a shape which complies with the legal pattern of light intensity as shown in Fig. 7.

The law requires that the specified pattern of light intensity, Fig. 7 must be achieved by the location of a light source of 21 candle power placed at or about the focal point of each reflector. It is, therefore at all times understood when the reflector herein described is used for projection of light in an automobile head lamp that the source of light of this candle power must be placed at or about the focal point which is 1.22 inches in the specified design.

The following table has been ascertained mathematically and is used to prepare a templet. The surface of a die is then shaped to the curve of the templet by rotating the die past cutters until its surface at all times touches the surface of the templet when the templet is axially positioned. The various sections as shown in Fig. 9 are then laid off on the die surface, and the surface of each of the sections is then shaped as shown at G in Fig. 6. The reflectors are drawn from this die by any skilled metal worker, but particularly by a recently developed process which may form the subject of a separate application.

Table—Hyperbolic curve—1.22" focus—Spread 6°.

Angle.	Radius.	Angle.	Radius.
0°	1.220"	85°	2.275"
10°	1.231"	90°	2.480"
20°	1.260"	92°	2.572"
25°	1.282"	94°	2.672"
30°	1.310"	96°	2.779"
35°	1.345"	98°	2.895"
40°	1.386"	100°	3.021"
45°	1.435"	102°	3.156"
50°	1.492"	104°	3.304"
55°	1.559"	106°	3.464"
60°	1.637"	108°	3.639"
65°	1.728"	110°	3.829"
70°	1.834"	112°	4.019"
75°	1.958"	114°	4.269"
80°	2.103"	116°	4.523"

What I claim is:

1. A light projecting reflector comprising a number of wedge shaped surfaces ar.

- ranged side by side with the wider portions all lying on one side of the axis of the reflector, said surfaces having their bounding edges in planes converging to a concentrated or small area at one side of the periphery of the reflector, each surface being distorted from a surface of revolution and the elements joining the bounding edges of each surface being straight and the elements 10 of the different surfaces radiating from differently located loci.
2. A concave reflector comprising a number of wedge-shaped surfaces, the bounding edges of which lie in planes which converge 15 towards each other from one side of the reflector through the reflector to the other side thereof and which meet in a concentrated or small area beyond the periphery of the reflector, each surface being distorted 20 from a surface of revolution and the elements joining the bounding edges of each surface being straight lines and the elements of the different surfaces radiating from differently located loci.
3. A concave reflector comprising a number of wedge-shaped surfaces lying in substantially the same direction, said surfaces having their bounding edges in planes converging to a concentrated or small area at 30 one side of and beyond the periphery of the reflector, and narrow strips lying between adjacent wedge-shaped surfaces, said strips being sections of a stigmatic surface of revolution as described.
4. A concave reflector symmetrical with respect to a vertical plane passed through the axis of the reflector, and including a number of wedge-shaped surfaces, the bounding edges of the surfaces being in planes which converge from the widest portion 40 of each surface to said first mentioned plane, and meet the same in lines entirely outside the periphery of the reflector, each surface being distorted from a surface of revolution and the elements joining the bounding edges of each surface being straight lines and the elements of the different surfaces radiating from differently located loci.
- revolution and the elements joining the 45 bounding edges of each surface being straight lines and the elements of each of the different surfaces radiating from differently located loci.
5. A concave reflector symmetrical with respect to a vertical plane passed through the axis of the reflector and including a number of wedge-shaped surfaces, the bounding edges of the surfaces being in planes which converge from the widest portion 50 of the surfaces to said first mentioned plane and meet the same in lines entirely outside of the periphery of the reflector, and narrow strips lying between adjacent wedge-shaped surfaces, said strips being sections of a stigmatic surface of revolution.
6. A reflector having the general shape of a surface of revolution of a conic section, said reflector including tapered sections or zones lying side by side and extending from one edge of the reflector to the other, each tapered surface or zone being distorted 55 from a surface of revolution and the elements which generate the respective tapered surfaces or zones and which join the opposite edges of these surfaces or zones radiating from differently located loci.
7. A reflector having the general shape of a surface of revolution of a conic section, said reflector including sections or zones, 60 the bounding edges of which lie in the surface of revolution, the respective surfaces of which are distorted from the surface of revolution and the elements which generate said surfaces or zones and which join the 65 opposite edges of these sections or zones radiating from differently located loci, and narrow strips lying between adjacent sections or zones, said strips being sections of a stigmatic surface of revolution.

In testimony whereof I hereunto affix my signature.

JOHN G. BALSILLIE.
